UNITED STATES PATENT OFFICE

WILLIAM ADAMS, OF LAWRENCE, AND CORNELIUS W. WICKERSHAM, OF CEDARHURST, NEW YORK, ASSIGNORS TO ADWICK CORPORATION, OF NEW YORK, N. Y., A CORPORATION OF NEW YORK

SPARK ARRESTER

Application filed November 10, 1927. Serial No. 232,325.

This invention relates to spark arresters and more particularly to arresters for use in connection with chimneys of residences or factories.

Heretofore numerous types of spark arresters have been built for use in connection with the chimneys and smoke stacks of industrial plants such arresters usually being of complicated construction and expensive to manufacture. The arresters of the type heretofore constructed are not practicable for general installation and use in connection with the chimneys of ordinary business structures and residences. To be readily adaptable to this use an arrester must be of simple construction, easily installed and inexpensive to manufacture.

Accordingly an object of the invention is to provide a new, simple, and efficient spark arrester adapted for the said use.

Other objects, features and advantages of the present invention may be more readily ascertained by reference to the following detailed description read in the light of the accompanying drawings, wherein

Fig. 1 is a side elevation of a device embodying the invention, and

Fig. 2 is a bottom view of the same device showing the construction thereof in full detail.

Referring now to the drawings, 10 indicates a hollow shell of shape substantially conforming to the interior of a hollow tile of the type commonly used in the flues of chimneys both for ordinary business and residential structures. The shell 10 is provided with an external flange 11 at the top thereof and extending about all sides thereof, such flange being formed as an integral part of the material comprising the shell 10. Inasmuch as the shell 10 is composed of a single piece of material such as galvanized iron it becomes necessary to cut the corners of the flange 11 into a plurality of tabs as indicated at 12. Wire cloth 20 of any suitable mesh may then be placed upon the flange 11 and bound in place by means of a binding strip 13. The binding strip 13 is composed of a single piece of flat material similar to that composing the shell 10, being of width sufficient to permit a por-

tion thereof to be folded under the flange 11 as indicated at 14 and also to permit the top portion thereof to be of a width substantially equal to the width of the flange 11. As indicated clearly in Fig. 2 the corner portions 55 of the binding strip 13 are cut in the shape of a plurality of tabs 15 which in the assembly of the device are folded over so as to partly overlap each other as shown in three corners of the device in Fig. 2. That portion of the 60 wire cloth lying between the edges of the binding strip 13 is bent upwardly from both sides and ends into a substantial convex formation uniformly over the width and length thereof.

It will be observed by reference to Fig. 1 that the shell 10 is of such size as to closely fit within a hollow tile indicated at 16 and to be held in place against downward movement by the flange 11 which overlaps and rests upon 70 the top of the tile. For this reason the device presents an arrangement which may be easily installed and which may be quickly removed for repairs or for any purpose desired. Its weight together with the frictional engagement thereof with the inner wall of the tile 16 are sufficient to hold the arrester in place without the use of cement or other binding material. Being composed of a minimum of parts, the manufacture of the 75 same is facilitated, thereby reducing the cost of production. As the tiles employed for the flues of chimneys are of standard shapes, the improved spark arrester may readily be manufactured in quantities for general use.

What we claim as new and desire to secure by Letters Patent of the United States is:

1. A device of the character described comprising a polygonal-shaped hollow shell, said shell being provided with an external flange 90 extending at right angles from the top thereof, wire mesh cloth covering the top of said shell and resting on said flange and a binding strip binding said wire mesh cloth to said flange.

2. A device of the character described comprising a substantially rectangular-shaped hollow metallic shell provided with an external flange extending at right angles from the top thereof and formed as an integral 100

part of the shell, wire mesh cloth covering the top of said shell and resting on said flange, and a metallic binding strip holding said wire mesh in place, said wire mesh being bent upwardly from the sides and ends of the shell into a substantially uniform convex shape.

3. A device of the character described comprising a hollow shell, said shell being provided with an external flange extending at 10 right angles to the top of the shell, wire mesh cloth covering the top of the shell and resting on said flange, a binding strip holding said wire mesh in place, said strip being of such width as to substantially cover said flange, 15 said device being adapted to fit within and conform to the interior of a hollow tile and to be supported by the contact of the flange thereof with the top of the tile.

In testimony whereof, we have signed our names to this specification.

20 WILLIAM ADAMS.
CORNELIUS W. WICKERSHAM.
